CLAIM

The ornamental design for a compact fluorescent lamp unit, as shown and described.

DESCRIPTION

FIG. 1 is a side elevational view of a compact fluorescent lamp unit embodying our new design; and FIGS. 2 and 3 are top and bottom plan views, respectively, thereof;

The side of the cover component that comprises the top portion of the compact fluorescent lamp unit embodying our new design and is not shown in the drawing is identical to that which is shown in the elevational view.

FIG. 2

FIG. 1

FIG. 3
